UNITED STATES PATENT OFFICE

2,073,065

CHAIR

Herbert M. Kahn, Appleton, Wis.

Application July 6, 1936, Serial No. 89,135

2 Claims. (Cl. 155—172)

The invention relates to chairs and particularly to high chairs for children.

It is an object of the invention to provide a foot rest which may be conveniently and rapidly adjusted to meet the requirements of a growing child.

It is a further object of the invention to provide a foot rest which may be conveniently adjusted without interference with the front legs of the chair, so that carvings or varying diameters of the legs may be disregarded.

It is also an object of the invention to provide in a high chair means for securing a foot rest for vertical adjustment but free from contact with the front legs.

With these and other objects in view, which will become apparent from a perusal of the description of the invention, the latter comprises the means described in the following specification, particularly pointed out in the claims forming a part thereof, and illustrated in the accompanying drawing, in which:

Fig. 1 is a perspective view of a high chair constructed in accordance with my invention.

Fig. 2 is a section on the line 2—2 of Fig. 1, and Fig. 3 is a section on the line 3—3 of Fig. 2.

Referring to the several views of the drawing, 10 generally designates a high chair which comprises a seat 11 supported on front legs 12 and rear legs 13 and provided with a back 14. A tray or shelf 15 is provided with rigid side arms 16 hingedly secured to the side edges of the back. A strap 17 is fastened to the lower side of the tray and is detachably secured to the under side of the seat to hold the tray down. The front legs are connected by a rung 18 and a pair of vertical stay rods 19 extend between the seat and the rung 18.

A foot rest 20 is made up in sections 21 and 22,

held together by a single screw 23. The foot rest 20 provides apertures 24 to clear the stay rods and, upon tightening of the bolt 23, the foot rest is clampingly secured to the stay rods.

Attention is called to the fact that the foot rest does not engage or come in contact with the front legs, so that irrespective of varying diameters of the legs or their slanting arrangement, the foot rest may be adjusted with convenience and dispatch on the vertical stay rods over a considerable range.

While the drawing shows a preferred embodiment of the invention, various changes and alterations may be made without departing from the spirit of the invention. I, therefore, do not limit myself to the details of construction and arrangement, as shown, but wish to include all variations and revisions and modifications constituting departures within the scope of the invention, as defined in the appended claims.

I claim:

1. In a high-chair having a seat supported on front and rear legs and a rung connecting said front legs, stay rods connecting said seat and said rung, a foot rest on said rods free from contact with said front legs comprising a front section and a rear section embracing said stay rods, and means for adjustably clamping said sections on said stay rods.

2. In a high-chair having a seat supported on front and rear legs and a run connecting said front legs, stay rods connecting said seat and said rung, a foot rest on said rods free from contact with said front legs comprising a front section and a rear section embracing said stay rods, and a single means for adjustably clamping said sections on said stay rods.

HERBERT M. KAHN.
